UNITED STATES PATENT OFFICE.

SYLVESTER LEO GOOKIN, OF BOSTON, MASSACHUSETTS, ASSIGNOR TO UNITED SHOE MACHINERY CORPORATION, OF PATERSON, NEW JERSEY, A CORPORATION OF NEW JERSEY.

MACHINE FOR INSERTING FASTENERS.

Application filed April 12, 1920. Serial No. 373,219.

To all whom it may concern:

Be it known that I, SYLVESTER L. GOOKIN, a citizen of the United States, residing at Boston, in the county of Suffolk and State 5 of Massachusetts, have invented certain Improvements in Machines for Inserting Fasteners, of which the following description, in connection with the accompanying drawings, is a specification, like reference characters 10 on the drawings indicating like parts in the several figures.

This invention relates to fastener inserting machines and is disclosed herein as embodied in an eyeleting machine equipped to 15 insert blind and invisible eyelets in the manufacture of boots and shoes.

Blind and invisible eyelets are ordinarily inserted in shoe uppers by a machine having a set provided with a clenching shoulder 20 of small diameter arranged to be inserted through a hole pinched in one of the layers of the shoe upper to meet the entering end of an eyelet barrel introduced from the other side of the shoe upper. Thus the eye- 25 let barrel is clenched between the layers of the upper after the layers have been permanently secured together and without disturbing their relation to one another.

This operation has been performed in the 30 past both by machines having a separate punch and set operating alternately as the work is fed through the machine and by machines having a combined punch and set which first punches a hole in the shoe upper and later clenches the eyelet between the 35 layers without having been withdrawn from the hole in the upper. The latter type of machine has become very popular for this operation and at the present time is 40 ordinarily used for it. It is in connection with the insertion of invisible eyelets by a machine of this type that the present invention is disclosed.

It is usual when setting eyelets in this 45 manner to punch a hole somewhat smaller than the diameter of the eyelet barrel so that the eyelet will be firmly secured to the material when it is clenched. Indeed, where a combined punch and set is used 50 to insert eyelets, the hole is necessarily smaller than the eyelet barrel since the pilot of the setting tool, which must enter the end of the eyelet barrel, serves as a punch to

form the hole. From this it follows that after the eyelet is clenched in the work it 55 adheres to the setting tool with considerable tenacity.

It is an object of the present invention to provide a stripper adapted to use in the setting of blind and invisible eyelets and 60 arranged to strip the work from the setting tool after an eyelet has been clenched. As herein disclosed, this stripper is carried by a part of the machine separate from the setting tool, the stripper and setting tool 65 being relatively movable so that in the cycle of operation of the machine the stripper may positively strip the work with the clenched eyelet in it from the setting tool, and is movable laterally in unison with the 70 work, to facilitate the feeding of the work. As illustrated, this stripper member serves also as an abutment to limit the movement of the work past the setting shoulder of the tool so that the eyelet may be relieved 75 upon to pass through the layer upon which it is to be clenched. The stripper is arranged to co-operate also with the complementary set which introduces the eyelet into setting position and serves to apply clenching 80 pressure to the eyelet, so that after the prongs in the eyelet barrel have been deflected by the clenching shoulder between the layers of the work they will be further 85 squeezed so as to flatten them and tighten 90 their hold upon the work. With this object in view and also in order to secure an efficient stripping and work-positioning action, the stripper member is illustrated as provided with a hole only as much larger than 95 the setting shoulder of the tool as is necessary to provide a satisfactory working clearance.

In order that the stripper may not interfere with the punching operation of the combined punch and set and at the same 100 time may be properly located to perform its stripping, work-positioning, and eyelet-tightening operations, provision is made for relative movement of the stripper and the set so that the stripper is comparatively remote from the cutting edge of the punch during the punching operation and is nearer to that cutting edge and appropriately located relatively thereto to position the work with respect to the setting shoulder at the 105 time of the clenching operation.

While the invention is illustrated in connection with a "right-side-up" eyelet-setting machine arranged to insert eyelets with their flanges uppermost, and while the invention is well adapted to such a machine, it should be borne in mind that it is shown in connection with that machine primarily for purposes of illustration, and that its utility is not limited to use in that connection since, evidently, in various of its aspects it may be used in connection with other types of machines.

With the above and other objects and features in view, the invention will now be described in connection with the illustrated machine and pointed out in the claims.

Referring to the drawings,

Fig. 1 represents a perspective view of a portion of an eyeleting machine including the work-engaging instrumentalities and embodying one practical adaptation of the present invention;

Fig. 2 is a view partly in elevation and partly in vertical section including the work-engaging instrumentalities in their initial positions, the punching tool being about to punch a hole in a piece of work comprising a plurality of superposed layers;

Fig. 3 shows the punching elements in the act of completing the hole in the work;

Fig. 4 is a view similar to Fig. 2 but showing the punching tool as having fed the work from punching position to eyelet-receiving position;

Fig. 5 is a view partly in elevation and partly in section of the elements at the right of line 5-5 of Fig. 2, the direction of view being indicated by an arrow and the work being omitted;

Fig. 6 is a sectional view on a larger scale showing the eyelet-inserting tool and the clenching tool at an intermediate position during the eyelet-setting operation, in combination with means arranged to sustain the work against the stress caused by the inserting of the eyelet;

Fig. 7 represents the eyelet-setting instrumentalities in co-operative relation at the instant of completing the clenching of the eyelet, such clenching being effected in part by the means whereby the work is sustained against the stress caused by inserting the eyelet;

Fig. 8 represents a top plan view of the regulatable mechanism for imparting feeding movement to the clenching tool; and

Fig. 9 represents a perspective view of a fragment of an article of work such as the quarter of a boot or shoe.

In order to avoid unnecessary drawing and description no attempt has been made to disclose herein a complete eyeleting machine, but since the machine selected for the purpose of showing one practical embodiment

of the invention is similar to that illustrated and described in United States Letters Patent 1,334,238, granted March 16, 1920, on an application filed by Perley R. Glass, reference may be made to the said patent for details of construction and operation not herein disclosed.

In the illustrated machine the eyelets are supplied to an inserting tool 10 by a raceway 11, the inserting tool being provided with a spring-pressed spindle 12 arranged to pass through the barrel of the leading eyelet 13 in the raceway and thereby to detach the eyelet from the raceway in consequence of retracting the latter transversely of the axis of the spindle. The inserting tool is reciprocated endwise and its movement is guided by a stationary bearing 14 in the frame of the machine.

The tubular clenching tool is provided with a clenching shoulder 15 of such form and arrangement that it is adapted to go through a layer of the work so as to perform its clenching function between two superposed layers, as shown by Figs. 6 and 7. This tool is provided with a hollow pilot portion 16 one function of which is to guide the barrel of the eyelet to the clenching shoulder and another function of which is to punch a hole in the work to receive the eyelet. For the latter purpose the tool is formed with a central bore 17 through which the punchings pass, the end portion 16 being so thin, if not actually sharp, as to cut a hole in the work. In order to complete the punching equipment the machine is provided with a punch-bed or block 18 which, as shown, is rigidly fastened to a carrier 19. This carrier is provided with a shank-portion 20 and the latter is arranged to slide lengthwise in a bearing provided by a laterally adjustable slide 21.

The punch-bed and the inserting tool are separated laterally one from the other a distance corresponding to the desired spacing between successive eyelets in the work, and the punching, feeding and clenching tool is accordingly shifted laterally from the punch-bed to coaxial registration with the inserting tool for the purpose of feeding the work after having punched it and before the eyelet is inserted. The amplitude of lateral motion of the feeding tool will vary according to the desired spacing of eyelets, and the operating mechanism by which the feeding motion is imparted is regulatable for varying the extent of feeding motion.

The feeding tool is arranged to slide endwise relatively to a feed-carriage 22 the motion of which is guided by rods 23. The mechanism shown by Fig. 8 for reciprocating the feed-carriage includes an oscillatory arm 24, a rockshaft 25, an arm 26 affixed to the rockshaft, transmission links 27 and 28

pivotedly connected one to the other by a pin 29, a link 30 arranged to constrain the movement of pivot 29 to a segmental path, and suitable means (not shown) for imparting 5 longitudinal reciprocation of uniform amplitude to the link 28. The arm 24 is oscillated by the rockshaft 25 but is connected to the latter by an adjustable connection indicated as a whole at 31 and of such construction 10 and arrangement as to provide for angular adjustment of the arm relatively to the rock-shaft. The outer end of the arm is forked and embraces a block 32 that is carried by the feed-carriage and connected thereto by 15 a pivot member 33. The construction and arrangement of the mechanism is such that the left-hand limit of motion of the feeding tool is in every case coincidental to the axis of the inserting tool 10 whereas the right-hand limit of motion is variable according 20 to the amplitude of spacing for which the mechanism is regulated. Such regulating is effected by varying the location of the pivot member 34 to which the link 30 is anchored. 25 As shown, the anchoring pivot 34 is carried by an oscillatory regulator 35 arranged to oscillate about a stationary pivot member 36. The regulator is provided with a handle 37 that overlies a stationary plate 38 in which 30 numerous holes 39 are formed for the reception of a stop-pin 40. So long as the regulator remains in one position the amplitude of feeding motion will remain constant but whenever the regulator is swung to a 35 new position the change of location thereby effected with respect to the anchoring pivot 34 amplifies or decreases, as the case may be, the extent of motion transmitted to the feed-carriage. 40 The regulator also serves to effect a corresponding change in the location of the punch-bed 18 so that the latter will be spaced from the axis of the inserting tool according to the amplitude of lateral motion 45 to be imparted to the feeding tool. For this purpose the regulator is provided with a cam-slot 41. This slot is occupied by a cam-roll 42 carried by a lever 43, the pivot member of which is indicated at 44. A universal 50 joint of suitable construction, indicated as a whole at 45, forms connection between the lever 43 and the slide 21.

Although the drawings do not include any 55 means for controlling the holder 19 with respect to movement toward and from the work, any suitable means such as that shown in the aforesaid Patent 1,334,238 may be provided for sustaining the holder rigidly against the punching stress executed by the 60 punching tool 16.

A stationary work-table is provided for supporting the work in co-operative relation to the several tools, said table comprising an elevated work-engaging portion 46 and having a slot 47 extending parallel to

the lines of feeding motion to receive the feeding tool and to receive a flat work-sustaining member 48. The holder 19 carries also a presserfoot 50, the latter being movable toward and from the work-table relatively to the holder and being guided in such movement by confronting portions 51 of the holder between which the shank portions of the presserfoot are arranged to slide. Preferably the holder 19 is bored for the reception of a compression spring, as shown in the aforesaid patent, the function of said spring being to maintain a downward pressure on the presserfoot so that the latter will function continuously in conjunction 80 with the work-table to clamp the work.

The specimen of work illustrated comprises a plurality of superposed layers 52, 53 and 54 of which the bottom layer would be the outside of the upper in the case of invisible eyeleting and of which the top layer would be the outside of the upper in the case of blind eyeleting. The other layers would be the lining and the eyelet-stay. In some shoes the lining may be interposed between the eyelet-stay and the upper while in others the eyelet-stay may be interposed between the lining and the upper.

The punching, feeding and clenching tool is affixed to and carried by a holder 55 and the latter is arranged to slide endwise in a bearing afforded by the feed-carriage 22. Any suitable mechanism may be provided for reciprocating the holder, the mechanism shown including toggle members 56 and 57, and a connecting rod 58 arranged to operate them. The member 57 is mounted upon a stationary pivot member 59. The joint connecting the two toggle members and the rod 58 is formed by a pivot member 60. The connection between toggle member 56 and the holder 55 is formed by a pivot member 61, and the latter is elongated so that it may maintain operative connection with the holder 55 without requiring the toggle members 105 to partake of the feeding motion.

The elements thus far described operate as follows: Starting from the position shown by Figs. 1 and 2, which represent the initial positions of the several instrumentalities, the punching tool rises until it engages the punch-bed 18 as shown by Fig. 3, thus punching a hole through all the layers of the work. In most cases the punching operation would result in passing the clenching shoulder 15 partway if not entirely through the lower layer 52 but this would obviously not be the case if the aggregate thickness of the layers were less than the distance between the clenching shoulder and the upper end of the punching tool. The pivot member 60 is carried past "dead center" as a continuation of its punching motion, thereby retracting the clenching shoulder 15 to the critical position, rela- 115 120 125 130

tively to the member 48, for clenching the eyelet. This refractory motion may be, and preferably would be slight, so as to avoid withdrawing the pilot portion from the work. Furthermore it relieves the pressure of the punch against the punch-bed before the tool moves laterally. From the position shown by Fig. 3 the punching tool moves from right to left for the purpose of feeding the work from the punching locality to the eyelet-setting locality where the punching tool will occupy the position shown by Fig. 4. While the punching and feeding motions are occurring the inserting tool 10 15 will descend and the raceway will be retracted so that an eyelet will be taken from the raceway and carried to the position shown by Fig. 4. The inserting tool and the clenching tool, being now in coaxial registration, will remain so while the inserting tool continues to descend. The barrel of the eyelet will be forced downwardly by the inserting tool and will pass from the spindle 12 to the pilot portion 16 of the clenching 20 25 tool and will eventually be turned outwardly by the clenching shoulder 15, as shown by Fig. 6, and ultimately clenched as shown by Fig. 7, after which the setting tools will be retracted to their initial levels 30 and the clenching tool will also be shifted laterally to its initial position as shown by Fig. 2.

During the operation of inserting the barrel of the eyelet through the layers 54 and 35 53 the tendency of the eyelet is to force the work toward and past the clenching shoulder, the tendency varying according to the density and thickness of the work. In some 40 cases the resistance offered by the eyelet-receiving material to the passage of the eyelet therethrough is so great that one or both of said layers would be pushed beyond the clenching shoulder if some means were not 45 provided for arresting them against the stress exerted by the eyelet. Successful results require, in every case, sustaining the work at a position relatively to the clenching tool such that the clenching shoulder will lie between the two layers where it is 50 desired to have the clenched portions of the eyelet lie. Accordingly, means is provided for insuring that relation between the work and the clenching shoulder, regardless of 55 variations in the physical properties and thickness of the several elements comprised in the work. In the illustrated embodiment of the invention the member 48 accomplishes this result. This member as shown is supported independently of or otherwise than 60 by the tool-holder 55 and is therefore capable of functioning more effectively than it could if it were carried by the latter. It is, however, preferably movable laterally in unison with the clenching tool so that it 65 will always occupy the desired relation

thereto. As shown, it is fastened to and carried by the feed-carriage 22 and its connection with the carriage is preferably such as to make it rigid with respect to its several functions. As shown by Fig. 1 the feed-carriage is provided with a groove in which the shank portion of the member 48 is fitted. A set screw 68 is carried by the carriage and has a tapered end arranged to engage the lower end of the member 48 to adjust the latter vertically. A clamping screw 65 extends through a slot 66 in the shank of the member 48 and has screw-threaded connection with the feed-carriage so that the head of the screw will bind the shank securely to the carriage when the screw is set up tightly. The member 48 will preferably be adjusted so that its upper surface will be below the work-sustaining surface of the table 46 to avoid friction with the work and the tendency to shift the work in the wrong direction when the feed-carriage is moving in the direction opposite to its feeding motion. On the other hand the distance between the top of the member 48 and the work-supporting surface of the table 46 is preferably very slight in order to avoid appreciable distortion of that portion of the work that bridges across the slot 47 in the work table, since, during the operation of inserting the barrel of the eyelet into the work, the downward pressure of the eyelet on the work depresses the bridging portion of the work. Although the member 48 is shown as embodying an L-shape, its proportions are such that it is, to all intents and purposes, rigid with respect to its effects on the work. The overhanging portion of the member 48 is preferably smooth and flat in order to avoid marking the work, and is provided with a hole 67 through which the clenching tool passes in order to co-operate first with the punch-bed and afterward with the inserting tool. The rim of the hole is preferably rounded in order to avoid scoring the layer 100 105 110 115 120 125 130 135 140 145 150 155 160 165 170 175 180 185 190 195 200 205 210 215 220 225 230 235 240 245 ally between the layers 53 and 52. As the leading end of the eyelet moves away from the setting shoulder it lies on the upper surface of the layer 52 which continues to be sustained by the member 48, and at the moment when the clenching is completed the clenched portion is subjected to a pressure caused conjointly by the inserting tool and the member 48 within the area covered by the clenched portion. In this respect the member 48 is supplemental to the clenching shoulder 15 in determining the ultimate form of the clenched portion, and the latter is flattened more than it would be in the absence of the sustaining action of the member 48. This feature is advantageous since it reduces the lump caused by the presence of the clenched portion between the layers, and furthermore it secures the eyelet more firmly in the work so that the likelihood of subsequent loosening of the eyelet due to the pulling of a lacing will be minimized. In order to oppose the tendency of the eyelet to tilt when subjected to the pulling stresses of the lacing it has been customary to provide the eyelet with a relatively broad flange 68, but for some kinds of shoes the manufacturers prefer a relatively narrow and inconspicuous flange. The supplementary effect of the member 48, whereby the clenched portion of the eyelet is flattened after it has been curved by the shoulder 15, renders the clenched portion adequate to overcome the tendency of the eyelet to tilt and loosen and therefore permits the use of an eyelet that has a relatively narrow flange 68.

It is to be observed that the member 48 does not partake of the endwise motion of the clenching tool and consequently when the tool is retracted after having completed the eyelet-setting operation the member 48, still sustaining the work, strips the latter from the clenching tool.

From the foregoing it will be seen that the member 48 performs three distinct functions: First, it insures the desired position of the clenching shoulder between two layers of the work; second, it flattens and tightens the clenched portions of the eyelet that have passed beyond the setting shoulder; and third, it strips the work from the clenching tool as the latter is retracted. It is also to be observed that since the member 48 is carried by the feed-carriage independently of the clenching tool it will partake automatically of variations in the amplitude of feeding motion so that it will always remain in registration with the clenching tool and at the same time be independent of all motions of the clenching tool lengthwise of its axis.

In adjusting the several work-engaging elements the preferred procedure would be as follows: First, to adjust the punch and

punch-block so that their conjoint operation will have the desired result, then to adjust the inserting tool with regard to the thickness of the work in which the eyelets are to be set, and to adjust the abutment, as often as may be necessary, according to the thickness of the layer that lies between it and the clenching shoulder at the moment of clenching. The foregoing order of procedure may be varied according to circumstances.

Having thus described my invention, what I claim as new and desire to secure by Letters Patent of the United States is:

1. A fastener-inserting machine having a setting tool formed with a clenching shoulder arranged to be inserted through one layer of the work to clench a fastener between adjacent layers of the work, a work-engaging member having a hole therein closely surrounding said setting shoulder, means for relatively moving said tool and said work-engaging member to carry said setting shoulder through said hole into and out of engagement with the work, and means to move said member and said tool in unison to feed the work.

2. A fastener-inserting machine having a setting tool formed with a clenching shoulder arranged to be inserted through one layer of the work to clench a fastener between adjacent layers of the work, a work-engaging member having a hole therein closely surrounding said setting shoulder, and means for relatively moving said tool and said work-engaging member to carry said setting shoulder through said hole into and out of engagement with the work.

3. An eyeleting machine comprising, in combination, eyelet-setting mechanism including a laterally movable tool having an eyelet clenching shoulder, and a work-engaging member having a hole forming a passageway for said shoulder, said member being movable laterally with the tool, and said tool being axially movable relatively to said work-engaging member so as to retract the clenching shoulder into said passageway after the clenching of an eyelet.

4. An eyeleting machine comprising, in combination, eyelet-setting mechanism including a tool having a punching portion and a clenching shoulder, said tool being movable laterally to one locality for punching the work and to another locality for clenching an eyelet, a stripper having a hole through which said shoulder is movable, and means for reciprocating the stripper laterally so as to maintain the hole in registration with said tool.

5. An eyeleting machine comprising, in combination, eyelet-setting mechanism including an axially movable tool having a punching portion and a clenching shoulder, said tool being also movable laterally to

one locality for punching the work and to another locality for clenching an eyelet, and a laterally movable stripper carried otherwise than by the clenching tool and relatively to which the said tool is movable toward and from the work.

6. An eyeleting machine comprising, in combination, eyelet-setting mechanism including an axially movable tool having a 10 punching portion and a clenching shoulder, said tool being movable laterally to one locality for punching the work and to another locality for clenching an eyelet, and a member movable laterally with the work, 15 and having a hole through which the setting shoulder and punching portion of said tool are movable toward and from the work, said member being constructed and arranged to strip the work from the tool.

7. An eyeleting machine comprising, in combination, eyelet-setting mechanism including a punching and clenching tool arranged to execute a lateral movement to feed the work from a punching locality 25 to a clenching locality, and a stripper carried otherwise than by said tool and arranged to move laterally in unison with said tool.

8. In a fastener-inserting machine, a fastener-inserting tool, a combined punch and 30 set acting also to feed the work, and work-engaging means relatively to which said combined punch and set is movable to punch and disengage the work, said means being arranged to strip the work from said combined punch and set.

9. In a fastener-inserting machine, a fastener-inserting tool, a punch-bed, a tubular punch movable relatively to said punch-bed 40 into engagement with said punch-bed to punch the work and also movable to feed the work, and a stripper arranged to partake of feeding movement of the punch but to remain stationary to strip the work 45 therefrom as the punch recedes from the work.

10. A fastener-setting machine comprising, in combination, fastener-setting mechanism including an inserting tool and a 50 fastener-clenching tool the former of which is movable toward and from the latter, the clenching tool being movable laterally while in the work to feed the latter, and means separate from the clenching tool and 55 arranged to sustain the work against the inserting stress of the inserting tool and to strip the work from the clenching tool.

11. An eyeleting machine comprising, in combination, a punch-bed, eyelet-setting 60 mechanism including a punching and clenching tool, regulatable mechanism for moving said tool laterally, while in the work, with variable amplitude to feed the work, and a stripper, relatively to which 65 the said tool is axially movable, arranged

to strip the work from said tool, said stripper being movable laterally by said regulatable mechanism with an amplitude commensurate with that of said tool.

12. An eyeleting machine comprising, in combination, a punching and feeding tool and regulatable mechanism including a feed-carriage arranged to move it from a variable punching locality to a fixed eyelet-setting locality, a punching bed arranged to co-operate with said tool, and a stripper fixed to said carriage and arranged to strip the work from said tool. 75

13. A fastener-inserting machine comprising a fastener-inserting tool, a punch-bed, a combined punch and set arranged to co-operate with said punch bed, a feed-carriage movable relatively to said punch-bed to impart work-feeding movement to said combined punch and set, and a stripper 80 carried by said feed-carriage independently of, but in co-operative relation to, said combined punch and set. 85

14. A fastener-inserting machine comprising fastener-inserting means, a tubular punch movable laterally to and from the fastener-inserting locality, means for shifting the punch laterally as aforesaid, and a stripper surrounding but spaced from said punch relatively to which the punch 90 and fastener-inserting means are movable toward and from the work. 95

15. An eyeleting machine comprising, in combination, a laterally movable work-feeding and eyelet clenching tool, a stripper 100 movable laterally therewith and arranged to strip the work therefrom, and means, relatively to which said tool is axially movable, for supporting the stripper.

16. An eyeleting machine comprising, in combination, a laterally movable punching and clenching tool and a stripper movable laterally therewith and arranged to strip the work therefrom, said stripper being adjustable independently of said tool. 105

17. An eyeleting machine comprising, in combination, a laterally movable tool constructed and arranged to feed the work by engagement with the wall of a punched hole in the work, means for retracting said tool 115 from the work after the latter has been fed, a stripper movable laterally with said tool and arranged to strip the work therefrom, and means arranged to sustain the stripper against moving away from the work 120 while said tool is being retracted.

18. An eyeleting machine comprising, in combination, eyelet-setting mechanism including an axially movable clenching tool having a clenching shoulder constructed and 125 arranged to go through a punched hole in a surface layer of a plurality of superposed layers of work so as to function between two layers, means for guiding said tool, and means attached to said guiding means and 130

arranged to surround the tool and bear on said surface layer adjacent to the punched hole so as to strip the work from said tool.

19. An eyeleting machine comprising, in

5 combination, eyelet-setting mechanism including an eyelet-inserting device, a clenching tool having a clenching shoulder constructed and arranged to go through a punched hole in a surface layer of a plurality of superposed layers of work so as to function between two layers, and means sustained otherwise than by said clenching tool and arranged to brace said surface layer adjacent to the punched hole so as to promote the transformation of the leading portion of the eyelet barrel beyond the clenching shoulder, said means and the clenching tool being arranged by relative movement to strip the work from the said tool.

20. An eyeleting machine comprising, in combination, eyelet-setting mechanism including a clenching tool having a clenching shoulder constructed and arranged to go through a punched hole in a surface layer 25 of a plurality of superposed layers, means for moving said tool laterally while in the work to feed the latter, and a stripper arranged to strip the work from said tool, said stripper being movable laterally with said tool.

21. An eyeleting machine comprising, in combination, eyelet-setting mechanism including a tool formed and operated to punch and feed the work and to clamp an eyelet 35 between superposed layers of the work, and a stripper movable in unison with the feeding movement of said tool but relatively to which said tool is axially movable to free itself from the work.

22. An eyeleting machine comprising, in combination, eyelet-setting mechanism including a clenching tool formed and operated to punch and feed the work, work-feeding mechanism including a feed-carriage by 45 which feeding motion is imparted to said tool, and a stripper carried by said carriage independently of said tool and arranged to strip the work from said tool.

23. An eyeleting machine comprising, in combination, eyelet-setting mechanism including a feed carriage, a clenching tool carried by the feed carriage and having a clenching portion formed to go through a layer of the work to clamp an eyelet between two confronting layers, a tool arranged to insert the eyelet through the other layer or layers, and means supported by the feed carriage for sustaining the work against the stress caused by the inserting of 55 the eyelet into the work.

24. An eyeleting machine comprising, in combination, eyelet-setting mechanism including an eyelet-inserting tool and a clenching tool the clenching shoulder of 65 which is formed and arranged to go through

a layer of the work so as to clamp the eyelet between two superposed layers, and means supported otherwise than by said clenching tool and arranged to function conjointly with the inserting tool to flatten 70 the clenched portion of the eyelet outside the area of the clenching shoulder and to strip the work from the clenching tool.

25. An eyeleting machine comprising, in combination, eyelet-setting mechanism including an eyelet-inserting tool and an eyelet-clenching tool having a clenching shoulder adapted to go through one layer of the work so as to function between superposed layers, and a stripper constructed and arranged to remain in one plane parallel to that of the work and to sustain the work against the stress of inserting an eyelet.

26. An eyeleting machine comprising, in combination, eyelet-setting mechanism including an eyelet-inserting tool and a laterally movable work-feeding and eyelet-clenching tool having a clenching shoulder adapted to go through one layer of the work so as to function between superposed layers, and a stripper relatively to which the clenching tool is movable toward and from the work, the stripper being movable laterally to and from stripping position.

27. An eyeleting machine comprising, in combination, a work-table having a recess, a stripper arranged in said recess, and eyelet-setting mechanism including an eyelet-inserting tool and an eyelet-clenching tool the former of which is arranged to insert 100 the eyelet from the opposite side of the work with respect to the location of the stripper.

28. An eyeleting machine comprising, in combination, a work-table having a recess, a stripper arranged in said recess and having a hole, and eyelet-setting mechanism including an eyelet-inserting tool and an eyelet-clenching tool the latter of which is movable toward and from the work through said hole.

29. An eyeleting machine comprising, in combination, a work-table, a feed-carriage, a stripper affixed to said feed-carriage and having a hole, and eyelet-setting mechanism including an eyelet-inserting tool and an eyelet-clenching tool the latter of which is carried laterally by said feed-carriage and arranged to move through said hole toward and from the work.

30. An eyeleting machine comprising, in combination, a work-table having a slot, a feed-carriage, a stripper affixed to the feed-carriage and arranged to occupy said slot, the stripper having a hole, and eyelet-setting mechanism including an eyelet-inserting tool and an eyelet-clenching tool the latter of which is carried laterally by the feed-carriage and arranged to move through 125 said slot toward and from the work.

31. In an eyeleting machine, eyelet-setting mechanism comprising, in combination, an eyelet-inserting tool, an eyelet-clenching tool having a clenching shoulder formed and arranged to go through a layer of work so as to function between two superposed layers, a work-engaging abutment arranged to sustain the work behind the clenching shoulder, and means for relatively moving said abutment and the clenching tool, after the latter has entered the work so as to establish a predetermined co-operative relation between them.

32. In an eyeleting machine, eyelet-setting mechanism comprising, in combination, an eyelet-inserting tool, an eyelet-clenching tool having a clenching shoulder formed and arranged to go through a layer of work so as to function between superposed layers, a work-engaging abutment arranged to sustain the work behind the clenching shoulder, and means arranged to cause relative movement of the clenching shoulder and said abutment, one toward the other, after the clenching tool has entered the work.

33. In an eyeleting machine, a punch-bed, and eyelet-setting mechanism comprising an eyelet-inserting tool, an eyelet-clenching tool having a punching portion arranged to cooperate with said punch-bed and having a clenching shoulder formed and arranged to go through a layer of the work so as to function between superposed layers, a work-engaging abutment arranged to sustain the work against the stress of inserting the eyelet, and means for relatively moving the clenching tool and said abutment during the interval between punching the work and clenching the eyelet, so as to establish a predetermined co-operative relation between the clenching shoulder and the abutment.

34. In an eyeleting machine, a punch-bed, an eyelet-inserting tool, an eyelet-clenching tool having a punching portion and a clenching shoulder formed and arranged to function between two superposed layers of work, an abutment arranged to sustain the work against the stress of inserting the eyelet, mechanism for operating said clenching tool so as to punch the work against the punch-bed, and thereafter to retract the clenching tool relatively to said abutment and to maintain the clenching shoulder in a predetermined co-operative relation to the abutment, and mechanism arranged to operate the eyelet-inserting tool so as to insert the eyelet and force it along the clenching shoulder while the aforesaid co-operative relation is maintained.

35. In an eyeleting machine, eyelet-setting mechanism comprising an eyelet-inserting tool, an eyelet-clenching tool having a clenching shoulder formed and arranged to go through a layer of the work so as to function between two superposed layers and

having a diametrically reduced portion behind the clenching shoulder, and an abutment formed and arranged to surround said reduced portion so as to sustain the work in a predetermined relation to the clenching shoulder, said abutment and reduced portion conjointly forming an annular space sufficiently wide to receive that portion of said layer that embraces said reduced portion of the clenching tool.

36. A fastener-setting machine comprising fastener-setting mechanism including a fastener-clenching tool having a portion arranged to go through one or more layers of the work, a tool-guiding element relatively to which said tool is movable toward and from the work, and a stripper affixed to said element.

37. A fastener-setting machine comprising a work-sustaining table having an opening, a member arranged in said opening and having a recess, and fastener-setting mechanism including a clenching tool movable into and out of the recess in said member, the latter being effective to strip the work from said tool in consequence of retracting the tool.

38. A fastener-setting machine comprising a work-sustaining table, fastener-inserting mechanism including a clenching tool movable upwardly to a clenching position at or near the plane of the table, and a stripper arranged to engage the under side of the work so as to strip the work from the tool as the latter moves downwardly.

39. A fastener-setting machine comprising a work-sustaining table, fastener-inserting mechanism including a clenching tool movable upwardly to a clenching position at or near the plane of the table, and a stripper arranged to remain at a constant level under the work but being adjustable to determine such level.

40. A fastener-inserting machine comprising a work-table, fastener-inserting mechanism including a clenching tool having a clenching shoulder formed and arranged to go through a layer of an article of work so as to function between two superposed layers, and a stationary stripper arranged to bear on said layer adjacent to said shoulder so as to prevent displacement of the work relatively to the table in consequence of retracting the clenching tool.

41. A fastener-inserting machine comprising a work-table, a work-engaging member fixed with respect to its distance from the plane of the table but being adjustable to determine such distance and having a passage-way for the reception of a clenching tool, and fastener-setting mechanism including a clenching tool movable relatively to said member and through said passageway.

42. An eyeleting machine comprising, in combination, eyelet-setting mechanism includ-

ing an inserting tool and a clenching tool constructed and arranged to clench an eyelet between two contiguous layers of an article of work, and means arranged to co-operate with the inserting tool to flatten the clenched portion of the eyelet, said means being arranged also to sustain the work against the stress of inserting the eyelet, said means and the clenching tool being relatively movable automatically to establish a predetermined relation between them prior to the clenching of the eyelet.

43. An eyelet-inserting machine having, in combination, an eyelet set having a clenching shoulder arranged to be introduced through one of the layers of the work to clench the entering end of an eyelet barrel between adjacent layers of the work, a strip-

per arranged to engage the work adjacent to the lacing hole in which the eyelet is inserted, and means for causing positive relative movement of the set and the stripper to strip the work from the set after the eyelet has been clenched.

44. An eyeleting machine having means for clenching eyelets between adjacent layers of the work and a work-stripper, said machine being organized to feed the work between successive eyelet-clenching operations, characterized by the fact that the stripper is arranged to be moved with the work-feeding element as the work is fed.

In testimony whereof I have signed my name to this specification.

SYLVESTER LEO GOOKIN.
